LIFT FOR DEEP WELL HYDRAULIC PUMPS

Elmo M. Knudson, Houston, Tex.

Application October 3, 1946, Serial No. 701,023

7 Claims. (Cl. 103—45)

1

The invention relates to a pump which is particularly adapted for deep wells to effect the elevation of the well liquid.

It is one of the objects of the invention to provide a deep well pump wherein the application and withdrawal of a pressure liquid serves to actuate a diaphragm so as to discharge and draw in a charge of well liquid.

Another object of the invention is to provide an elongated cylindrical diaphragm having an inherent resiliency which will encourage the entry of a charge of well liquid thereto.

Another object of the invention is to elevate well liquid by the collapse of a cylindrical diaphragm due to the application of hydraulic pressure thereto.

Another object is to provide a submersible motor and hydraulic pump in combination with a cylindrical flexible chamber to be filled by a well liquid due to the submergence thereof below the level of the well liquid.

Still another object is to provide a cylindrical pumping chamber to be collapsed by hydraulic pressure in order to expell well liquid therefrom.

Another object is to effect a pumping action to elevate well liquid by applying a hydraulic pressure to the exterior of a cylindrical pumping member.

Still another object is to apply an actuating liquid to the exterior of a cylindrical diaphragm so as to effect collapse thereof in elevating a well liquid and to withdraw such pressure to encourage the entrance of a charge of well liquid to be expelled by the return surge of such actuating liquid.

Another object is to provide a cylindrical diaphragm in a well pump assembly in combination with upper and lower standing valves so that the resiliency of the diaphragm will aid in the entry of a charge of well liquid due to the submergence of the pumps and by a vacuum created by the rotary pump, or both, and to thereafter discharge such sample upon the collapse of the diaphragm from an exterior liquid pressure.

Another object is to provide for a straight line flow of well liquid through a deep well diaphragm pump.

Another object is to provide a pair of cylindrical concentric chambers in a well pump where the inner chamber has a flexible wall subject to collapse due to pressure liquid in the outer chamber.

Another object is to provide a plurality of spaced hydraulically operable cylindrical dia-

2

phragm pumps in a well bore to elevate the well liquid by stage pumping.

Another object is to provide a submersible switch connection for deep well pumps so as to actuate or reverse a hydraulic pump operation.

Another object is to effect a surging action in a deep well hydraulic pump due to differential pressure on the inside and outside of a diaphragm construction.

Another object is to provide a control switch for a deep well hydraulic surge diaphragm pump wherein the switch operation is a function of the pressure applied to the diaphragm.

Another object is to provide a control of cycle operation by a surface clock for actuating and reversing motor.

Another object is to provide a deep well diaphragm pump actuated by a body of power liquid drawn from and returned to a reservoir in the well.

Another object is to provide a flexible cylindrical diaphragm in a well tubing in combination with a housing thereabout so that upon the application of pressure to the exterior of the diaphragm, a pumping action is obtained.

A still further object is to incorporate a flexible portion in a well tubing in combination with a pair of check valves at the ends thereof, so that the collapse and expansion to the portion will effect a pumping action.

Other and further objects of the invention will be readily apparent when the following description is considered in connection with the accompanying drawings wherein:

Figs. 1 and 2 when taken together show a side elevation of a well equipped with a pump assembly embodying the invention;

Fig. 3 is a broken vertical sectional view of the top of the assembly and showing the control switch;

Fig. 4 is a transverse section taken on the line 4—4 of Fig. 8;

Fig. 5 is a transverse section taken on the line 5—5 of Fig. 7;

Fig. 6 is a broken sectional view taken on the line 6—6 of Fig. 3; and

Fig. 7 is a broken vertical sectional view which is a continuation of Fig. 3 and showing the pumping chamber and diaphragm;

Fig. 8 is a broken vertical sectional view which is a continuation of Fig. 7 and showing the lower end of the pump;

Fig. 9 is a transverse section showing the structure to permit flow past the standing valve, and taken on the line 9—9 of Fig. 8.

Fig. 10 is a wiring diagram of an electrical control circuit.

Fig. 11 is a broken sectional view showing a modified arrangement of electrical control due to differential pressure.

Figs. 1 and 2 taken together show a combination assembly for the production of the well liquid such as oil. Such an arrangement is particularly adapted for a deep well and it is to be understood that the invention may be applied to wells where there may be a plurality of pumping stages or a single pumping assembly may be positioned in the well.

In Fig. 1 the casing 2 extends into the well and has the lower pumping unit 3 supported by a tubing 4 below the packer 5 which is in turn positioned by a tubing 6 connected to the upper pumping assembly 8. The upper tubing 9 extends to the surface.

As the oil or liquid being produced flows into the well, it will rise in the chamber 10 around the lower unit 3 and in this manner form a reservoir for liquid to be pumped. The packer 5 closes the casing.

The discharge from the lower pumping assembly 3 moves up through the tubing 4 and discharges from the outlet 12 into the upper reservoir 13 in the casing above the packer 5 which forms a barrier to prevent the down flow of liquid elevated thereabove by the unit 3. Such liquid will be drawn in by the pumping unit 3 at 28 and elevated to the surface through the upper tubing 9 where it is discharged to a pipe line storage or separator.

Figs. 3, 7 and 8 when taken end to end form a continuous vertical sectional view of one of the pumping units such as the unit 3 of Fig. 2. Such unit is made up of the housing 15 closed by a plug 16 and which carries the lower end of the tubing 4 which is adjustably positioned by means of the collars 17 and 18 which form a seal with the plug 16. In this manner, the housing 15 is entirely closed and it supports the pumping mechanism. The pumping mechanism is made up of the motor 20 and pump 28 shown in the base of the housing 15 at the bottom of Fig. 8. This pump is reversible, the electric motor receiving its current from the wiring circuit 21 which extends into the well through a cable 22.

Fig. 3 shows a plurality of conductors extending to the motor and these may be either three, four, five, or six in number, depending upon the size and type and operation of the motor.

Any desired type of control switch for the motor may be used and will be later described.

The pump as seen in Fig. 8 is arranged for operation so as to discharge upwardly through the conduits 22 into the power liquid chamber 23. The liquid is drawn into the pump through an opening 24 from the actuating liquid reservoir 28' inside of the housing 15.

When the motor is reversed, of course then the liquid is withdrawn from the power liquid chamber 23 through the conduits 22 and discharged into the opening 24 back into the reservoir 28'. In other words, when the motor operates in one direction, it pumps the liquid into the power liquid chamber and when reversed, it withdraws the liquid from such power liquid chamber.

The pumping portion of the assembly is best seen in Fig. 7 and includes the pipe or housing 25 which forms the wall of the pump chamber. This wall 25 of the housing is arranged to support a barrier 26 which in turn supports the upper end of the inlet pipe 27 through which the well liquid is drawn into the pumping assembly. The

inlet opening 28 allows such entry and the check valve 29 prevents a return flow of the liquid when pressure is applied in the power liquid chamber. In order to accommodate for expansion and prevent fluid loss, the upper end of the pipe 27 has the packing 30 thereon to form a seal inside the nipple 31.

The pumping operation is performed by the collapse and expansion of a cylindrical diaphragm 32 whose ends 33 and 34 are anchored in the nipples 35 and 36 respectively. The nipple 35 is the inlet nipple to receive the flow of well liquid from the pipe 27. It has a plurality of openings 37 therein which act more or less to prevent extruding into the chamber in nipple 35 of the diaphragm and to allow the passage of liquid into the interior chamber 38 known as the diaphragm chamber. The upper nipple 36 is of similar construction and discharges into the outlet pipe 40 which carries a standing valve 41 which is seen in the lower end of Fig. 3.

The passage 42 extends upwardly from the valve 41 which joins into the tubing 4 so that the liquid is elevated either to the surface or to the next stage of the pumping assembly such as the unit 8 in Fig. 1.

Particular attention is directed to the diaphragm 32. This diaphragm is cylindrical and may have a substantial length so that it may be collapsed due to the pressure or power of actuating liquid which is forced into the power liquid chamber 23. This pressure through the barrier 26 as seen in Fig. 5 exerted on the diaphragm causes the collapse thereof and the well liquid inside of the diaphragm is prevented from escaping downwardly by the check valve 29 so that it will be forced upwardly through and into the tubing. The control and time of the pump can be adjusted as desired and will be such that a predetermined pressure differential will be applied to the power liquid chamber 23 and diaphragm member 32 across the diaphragm in order to collapse and permit expansion of the diaphragm. When the differential pressure of 23 over 38 builds up to the predetermined amount, the pump control switches will be actuated so as to reverse the direction of the motor or to reverse the pumping operation. The liquid present in the pump chamber 23 is withdrawn upon reversal of the pump so as to relieve the pressure which collapsed the diaphragm from the outside. The diaphragm, being of a resilient material will have an inherent resiliency which tends to return it to its normal cylindrical configuration as seen in Fig. 7 so that it will tend to expand when the pressure on the outside of the diaphragm 32 is relieved.

In view of the positioning of the pumping unit 3 below the head of oil in the well or casing, the pressure of such column of oil causes the oil to flow into the chamber 38. There is thus a differential pressure across the diaphragm 32 and this differential can be used to control the operation or cycle as will be later described. The control may be adjusted to even draw a vacuum in the chamber 23 if desired.

The liquid which has been theretofore discharged is retained in the tubing above the diaphragm by the check valve 41. When sufficient time has elapsed to admit the liquid to set up the necessary differential, the pump is again reversed by the control mechanism and the cycle repeated by applying pressure in the power liquid chamber 23.

The timing cycle of the motor can be arranged in accordance with the well conditions and pump characteristics. The assembly is entirely en-

closed and the operation is simple and efficient. One form of the control mechanism is best seen in Figs. 3 and 6 and includes the Bourdon tubes 45 and 46, both of which are connected to a yoke contact member 47 so that any movement thereof will be due to the differential pressure existing between the two tubes. The Bourdon tubes, as is well known, are hollow curved tubes of a relative thin material which tends to straighten out when pressure is applied therein. The tube 45 is connected to a conduit or passage 50 which as seen in Fig. 3 extends downwardly through the body member 51 and into the area 52 as seen in the top of Fig. 7 which area forms the upper portion of the power liquid chamber 23 by virtue of the opening 53 in the top barrier 54. Thus any pressure existing in the pump chamber would be reflected by the movement of the Bourdon tube 45 so that the contact member 47 would move into engagement with the switch 48. This switch is arranged in a circuit 55 which extends to the surface through the conduit 22 and is connected with the motor switch in the switch box 56 on the surface. Thus when the pressure in the pump chamber builds up to a predetermined extent, in accordance with the adjustment of the control mechanism, the motor switch will be reversed so as to reverse the pump and consequently reverse the flow of pressure liquid from the pump.

The Bourdon tube 46 is connected into a conduit 57 best seen in Figs. 3 and 6 and is shown as extending into a groove and into the outlet pipe 48. This tube will thus reflect the pressure which is present in the chamber 38 inside of the diaphragm 32. In other words, when the pump is reversed and the pressure liquid withdrawn from the pump chamber 23, the pressure in the diaphragm chamber to which this Bourdon tube is connected will be substantially reduced.

When the pressure inside of the diaphragm is reduced below the pressure caused by the column of oil in the casing outside of the pumping unit, then of course the lower standing valve 29 will open and the well pressure will move into the diaphragm chamber. It will be understood that this well pressure is substantial because of the fact that the pump unit 3, Fig. 2, is immersed below the static head of the column of oil in the casing. This pressure moving into the diaphragm chamber 38 will be reflected in the bourdon tube 46 causing a straightening thereof and the movement of the yoke contact member upwardly until it engages the switch 48. It will be remembered that the tube 46 is meanwhile contracting due to the withdrawal of the pressure liquid from the pump chamber.

It seems obvious that the adjustment of the heads on the contact yoke member 47 can be arranged so as to obtain the reversing of the motor at the desired differential pressure which is always below the pressure at which the diaphragm 32 would be extended beyond its elastic limit.

Fig. 11 shows a modified form of the arrangement of Fig. 6 where the switches 48 and 49 have been dispensed with and a variable reactor 70 arranged to receive the core member 71 which is in turn connected at 72 to the yoke member 47. Movement of this core member will determine the control of the motor switches at the surface in the switch box 56.

A circuit for accomplishing desired control when using this form of the invention is shown schematically in Fig. 10 at 75. This circuit includes a transformer 76 at the surface through which energy is supplied to a bridge circuit 77, 75

including a rectifier 78 having a sensitive relay 79 connected to opposed points thereon. The bridge circuit includes conductors 80 which supply current to the reactor 70.

5 Before operation begins, the variable resistor 81 must be adjusted to equal the resistance of the control circuit between the controller or switch box 56 and the reactor 70. A reactor 82 in series with the resistor 81 is manually adjusted to the proper operating point. Operation is then as follows:

10 The operator presses the start button 82 to energize the relay 83 which is then maintained closed by the normally open contact 84. Another normally open contact 85 also closes to energize the transformer 76. When the bridge circuit 77 is in a balanced condition, no current flows through the rectifier 78 and the coil of the relay 79 of which the contacts remain normally closed. 15 The contacts 86 are energized through the normally closed contacts 86' of the relay 79. The "forward" coil 87 of the motor starter is energized through another normally open contact 88 and in this manner the motor 20 is energized in the forward direction.

20 As the conditions change in the hydraulic circuit until the Bourdon tubes 45 and 46 move the core 71 sufficient to unbalance the bridge circuit 77, such unbalance causes current to flow in the relay 79 whereupon its normally open contact 79' will close to energize the reverse relay indicated at 89. Relay 79 being located on the surface may be adjusted to operate at any desired differential pressure. The normally closed contact 90 will 25 open to de-energize the contacts 86 and 88 whereby current is supplied to the motor 20 to effect rotation thereof in the reverse direction.

30 It thus seems apparent that as the core 71 is caused to move in opposite directions, the motor 20 will be energized to rotate in proper direction to effect desired sequence in operation.

35 The operation of the device may be terminated at any time by pressing the stop button 91, however, if a parts failure prevents the pump from coming to the adjusted differential pressure, a time relay 92 is provided in the control circuit to operate the relay 84 at any time rotation of the motor in a given direction has exceeded a predetermined time interval.

40 Broadly the invention contemplates an automatically operating diaphragm pump for wells.

45 What is claimed is:

1. A deep well hydraulic pump including a well tubing for the flow of the well liquid being produced, a normally cylindrical resilient flexible diaphragm member sealed, an inlet and an outlet valve for said member to provide a diaphragm chamber, therein, and hydraulic pump means to alternately compress and allow expansion of said diaphragm to discharge liquid from and draw into such diaphragm a charge of liquid from the well being pumped respectively, said hydraulic means including a reservoir adjacent the diaphragm member, connections to a cylinder about said diaphragm for power liquid from said reservoir, an electric motor and power liquid rotary pump in one of said connections, switch means operable by the pressure of such power liquid and pressure in said pump member to alternate current to reverse said motor and pump to effect the pumping of power liquid into or out of said reservoir.

2. A deep well hydraulic pump including a tubing for the flow of the well liquid being produced, a normally resilient flexible diaphragm

member therein, an inlet valve and an outlet valve for said member to provide a pump chamber and sealed hydraulic pump means to alternately compress and allow expansion of said diaphragm to discharge liquid from and draw into such diaphragm a charge of liquid from the well being pumped respectively, said hydraulic means including a reservoir adjacent the diaphragm member, connections to a cylinder about said diaphragm for power liquid from said reservoir, an electric motor and power liquid rotary pump in one of said connections, switch means operable by the pressure of such power liquid and pressure in said pump member to alternate current to reverse said motor and pump to effect the pumping of power liquid into or out of said reservoir, said switch means in turn including a pair of Bourdon tubes or bellows, a rocker yoke connected thereto, and contact members operable by said yoke.

3. In a deep well diaphragm surge pump including a submersible reversible electric motor, a reversible rotary power liquid pump, a reservoir for power liquid connected to said pump, a power cylinder connected to said pump, a diaphragm to be compressed in said cylinder by the power liquid, and inlet and outlet valves for said cylinder so as to pump well liquid upon drawing in another charge of liquid from the well below the pump, an electric switch means to reverse said motor as a function of the pressure in said power cylinder and within said diaphragm.

4. A pump for wells including a tubing, a reservoir thereon for power liquid, a normally 35 resilient cylindrical diaphragm, a housing therefor, an electric motor and a power liquid pump connected to said reservoir and housing, said diaphragm comprising a flow passage for well liquid to said tubing, inlet and outlet check 40 valves for said diaphragm, and switch means operable as a function of the differential pressure across said diaphragm to reverse said motor and pump to alternately pump power liquid into said housing to compress said diaphragm to discharge well liquid and to draw out power liquid to allow the diaphragm to expand to allow entry of well liquid.

5. A deep well pump including a submersible reversible electric motor, a reversible rotary 50 power liquid pump, a reservoir for power liquid connected to said pump, a power cylinder con-

nected to said pump, a diaphragm to be compressed in said cylinder by the power liquid, inlet and outlet diaphragm valve for the well liquid so as to pump well liquid, an electric switch means to reverse said motor as a function of the pressure differential of power liquid and well liquid in diaphragm.

6. A pump for wells including a pump chamber in the well, a tubular diaphragm therein, means to admit and allow discharge of well liquid to the inside of said diaphragm, an actuating liquid on the outside, means to cause a flow of such actuating liquid into and out of said chamber, and additional means to control said first means which additional means is operable from the top of the well and includes a switch in the pump which moves as a function of the differential pressure across said diaphragm.

20 7. A pump for wells including a pump chamber in the well, a tubular diaphragm therein, means to admit and allow discharge of well liquid to the inside of said diaphragm, an actuating liquid on the outside of said diaphragm, pump means to cause a flow of such actuating liquid into and out of said chamber, and additional means to control said first means which additional means is operable from the top of the well as a function of the differential pressure across said diaphragm, said control means being adjustable to maintain a minimum operating differential.
